UNITED STATES PATENT OFFICE.

ELI COLLINS ESPEY AND ROBERT WELLINGTON HARRIS, OF PLEASANTON,
KANSAS.

SEWING-AWL.

SPECIFICATION forming part of Letters Patent No. 655,548, dated August 7, 1900.

Application filed April 3, 1900. Serial No. 11,331. (No model.)

To all whom it may concern:

Be it known that we, ELI COLLINS ESPEY and ROBERT WELLINGTON HARRIS, citizens of the United States, and residents of Pleasanton, in the county of Linn and State of Kansas, have invented a new and Improved Sewing-Awl, of which the following is a full, clear, and exact description.

Our invention is an improvement in the class of sewing-awls whose handles are provided with a recess or chamber to receive a thread-wound spool, from which the thread passes to the eye of the awl-point and is drawn off as required.

15 The invention consists of novel features and parts and combinations of the same, as will be fully described hereinafter and then pointed out in the claims.

A practical embodiment of the invention is 20 represented in the accompanying drawings, forming a part of this specification, in which similar characters of reference indicate corresponding parts in all the views.

Figure 1 is a perspective view of the improvement. Fig. 2 is a sectional plan view of the same on the line 2 2 in Fig. 3, and Fig. 3 is a transverse section of the same on the line 3 3 in Fig. 2.

The improved sewing-awl is provided with 30 a suitable handle A, carrying at its front end a chuck B for receiving and holding a needle C, of any approved construction. In one side of the handle A is arranged a longitudinally-extending recess A', through which extends a 35 spool-holder D in the form of a pin, having bearings in the ends of the handle A, as is plainly indicated in Fig. 2, the rear end of said holder being formed with a head adapted to be taken hold of by the operator for 40 withdrawing the holder from its bearing and allowing of removing an empty spool E from the holder or placing a filled spool on the said holder within the recess A'. The spool E carries the usual thread F, which unwinds 45 from the spool and extends first transversely through an eye G, mounted to slide longitudinally in a slotted guideway H, attached to one side of the handle A, the thread F leading from the outer end of the handle 50 alongside the handle to the eye of the needle C, as indicated in the drawings. The eye G

is pressed on by a coil-spring I, extending longitudinally in a recess A², formed in the handle A in the rear of the guideway H, the outer end of said spring being secured to the 55 back of the handle, as indicated in the drawings.

Normally the spring I holds the eye G in a rearward position; but when the device is used for sewing the eye G travels forward 60 and backward in its guideway H, according to the position of the coil of thread unwinding at the time from the spool E, to prevent tangling of the thread in the spool and in said eye. 65

In using the device the operator takes hold of the handle A in such a manner that the fingers extend through the opening of the recess A' to engage the spool E and the thread F, unwinding therefrom, and give the desired 70 tension to the thread as the latter unwinds from the spool in the operation of sewing, carried on in the usual manner. Thus by the operator's fingers engaging the thread and the spool in the recess A' more or less 75 tension may be given to the unwinding thread, according to the nature of the work in hand, and, furthermore, a proper unwinding of the thread is always insured, owing to the spring-pressed feed-eye G, movable longitudinally 80 in the guideway H.

By the arrangement described a large recess A' can be provided in the handle A to receive a very large spool filled with quite an amount of thread, so that the awl can be used 85 for a considerable length of time before the thread is used up and before a new spool needs to be inserted in the handle. By having the recess A' open at one side of the handle the operator can at any time see how much 90 thread is left on the spool, and in case but a small amount of thread is on the spool the operator can readily replace this spool with a filled one before beginning a new seam on the work in hand. 95

The needle C is provided with the usual eye for the passage of the thread, and the said needle is also preferably provided with a longitudinally-extending recess in the rear of the eye for guiding the thread to the needle-eye from the eye G. 100

Having thus fully described our invention,

we claim as new and desired to secure by Letters Patent—

1. An awl, comprising a handle having a recess formed in its side, a needle carried by said handle, a removable spool-holder held in the handle and extending longitudinally in said recess to receive and hold a spool with the thread thereon, a guide or feed eye mounted to slide longitudinally in said handle and arranged for the passage of the thread from the spool to the needle, and a spring controlling said guide or feed eye, as set forth.
2. A sewing-awl, comprising a handle having a lengthwise recess formed in one side, a needle carried by said handle, a spool-holder in the form of a removable pin held in said handle and extending through said recess

lengthwise thereof, said spool-holder being adapted to receive the spool, a slotted plate secured to said handle parallel to said recess, 20 a guide-eye mounted to slide on said slotted plate and adapted to guide the thread from the spool to said needle and a helical spring arranged lengthwise in the handle and connected with the outer end of same and to 25 said guide-eye, as set forth.

In testimony whereof we have signed our names to this specification in the presence of two subscribing witnesses.

ELI COLLINS ESPEY.

ROBERT WELLINGTON HARRIS.
